Miller Stansbury

UNITED STATES PATENT OFFICE

91,221

DESIGN FOR A RADIOCABINET OR THE LIKE

Miller Stansbury, Washington, D. C.

Application September 30, 1933. Serial No. 49,382

Term of patent 14 years

To all whom it may concern:

Be it known that I, MILLER STANSBURY, a citizen of the United States, residing at Washington, in the District of Columbia, have invented a new, original, and ornamental Design for Radiocabinets or the like, of which the following is a specification, reference being had to the accompanying drawing, forming part thereof, in which

Figure I of the drawing is a perspective view of my new design, Figure II being a side elevation of same.

I claim:

The ornamental design for a radiocabinet or the like, as shown.

MILLER STANSBURY.
